UNITED STATES PATENT OFFICE.

ABE. L. TEETOR, OF INDIANAPOLIS, INDIANA.

GRAIN-SCOURER.

SPECIFICATION forming part of Letters Patent No. 310,476, dated January 6, 1885.

Application filed March 29, 1884. (No model.)

To all whom it may concern:

Be it known that I, ABE. L. TEETOR, of Indianapolis, in the county of Marion and State of Indiana, have invented certain new and useful Improvements in Grain-Scourers; and I do hereby declare the following to be a full, clear, and exact description of the invention, such as will enable others skilled in the art to which it appertains to make and use the same.

My invention relates to an improvement in machines for cleaning and scouring grain, the object being to provide a device of this character which shall be adapted to first scour and polish the grain, then brush it, and finally to separate it from all damaged or defective grain and all foreign matter. A further object is to provide a cleaner which shall be simple and economical in construction, and at the same time durable and efficient in use; and with these ends in view my invention consists in certain details of construction and combinations of parts, as will be hereinafter described, and pointed out in the claims.

In the accompanying drawings, Figure 1 is a perspective view of my improved device. Fig. 2 is a view in vertical section. Fig. 3 is a view in horizontal section on the line *x x* of Fig. 2. Fig. 4 is a view in elevation of the feed-regulating device, and Fig. 5 is a front and top view of the separator.

A' represents the frame, constructed in any desired manner and of any suitable size. In the upper and lower cross-pieces of this frame is journaled the vertical shaft 1, to which is secured, near its lower end, the band-wheel 2, through which power is transmitted to the said shaft. To the end posts of the frame is secured a shelf or plate, *F*, provided with a central opening, and between which plate *F* and the cross-piece 3 of the frame is secured the outer scouring-case, *A*, preferably formed of perforated sheet metal, within which is placed the inner corrugated scouring-cylinder, *B*, somewhat smaller in diameter, and also perforated, as shown in the drawings. Below the plate *F* is located a brush, *C*, the upper part of the wooden portion of which is secured to the casing *K*, which latter is fastened to and operated by the shaft 1, the said wooden portion of the brush being provided with per-

forations or elongated slots *o*. Surrounding this brush is a perforated casing, *E*, secured to the plate *F* by means of bolts or rods *Y*, the bottom *H* of which is provided with an opening, through which passes the said casing *K*, and also with a flange, *n*, which extends upwardly into the space between the casing *K* and the inner surface of the wooden portion of the brush. Below the bottom *H*, and secured thereto by means of the metal casing *G'*, is the plate *I*, in which the lower end of the cylinder revolves, thus forming a chamber or opening, *V*, between the plates *H* and *I*, from which air is supplied through opening *G'* to the brush *C* by passing up through between the flange *n* and casing *K* and out through the perforations or slots in the wooden portion of the brush. The chamber *V* is in direct communication with the opening *G'*, and the chamber *V'* is in direct communication with the interior of the brush. Thus it will be seen that when the fan is started it draws the air from the chamber *V* up into and through the brush and down into the fan-casing, from which it is discharged.

The casing *E* is made adjustable around the brush by providing it with screw-threaded lugs *w* on either side of a slit running its whole length, and inserting in said lugs bolts *x*, by means of which the edges of the casing may be drawn together or forced apart, as desired, the lugs on one side being formed at a suitable distance from the edge in order to allow the edges to lap over, said edges being so lapped in the direction in which the brush travels that when the brush is in motion it will not injure the grain by forcing it against the edge of the casing, but will carry it off of it.

Below the chamber *V* is formed the fan-chamber *V'*, in which is located the fan *V²*, secured to the shaft 1, the top *J* of said chamber being provided with an opening, *L*, for the admission of the air, and also with an opening in the side to allow the air to escape.

Between the plates *J* and *F* is located the metal casing *G*, extending half-way round the machine, as shown in Fig. 3 of the drawings, and secured at its ends to the uprights *v*, which latter are sufficiently wide at their lower ends to be attached to the casing *G'* as high as the

plate H, from which point said uprights narrow or incline for the purpose of allowing a free passage for the air through the brush-easing down to the fan.

5 Fig. 4 shows my improved device for regulating the feed of the grain from the scouring chamber b to the brush. The dotted lines c represent small openings formed in the plate F at equal distances from each other.

10 T is a movable plate placed over the plate F, and also provided with openings c' c' and c² c², and with a laterally-extending arm, c³, the path through which the latter moves being indicated by a dotted line. The openings

15 c' in the plate T are formed twice as long as the openings c or c², so that when the arm c³ is moved to the point c⁵ the openings c' register with the openings c on opposite sides. If the plate T is moved still farther to the

20 point c⁶, it will gradually open or expose the remaining openings c c by registering the openings c² c² therewith, and when the arm reaches the point c⁶ it will plainly be seen that all the openings c will be open. By this arrangement

25 I am enabled to evenly distribute the grain to the brush, and to aid in this even distribution I form the upper head of the brush with a depression, d, immediately under the openings c in the plate F, through which the

30 grain falls, and then into said depression. When the brush is in motion, the centrifugal force will carry the grain over the sides of the head, and it will then drop down between said brush and the casing E. After the grain leaves

35 the brush it falls onto the plate H and fills the space between the brush-casing and the flange on the plate H. In this chamber or space the grain is carried around to a spout, e, by a projection, j, on the lower portion of the brush,

40 said pipe e leading from an opening in the plate H to the entering chamber of the separator D. This chamber is provided with the vertical partitions s and the inclined shelves g' h' i', one placed below the other, said partitions s extending but part way up the chamber, and forming tubes f, g, and h, which lead

45 up into the chamber S, the side t of the entering chamber S, extending somewhat above the partitions s, as shown in Fig. 5 of the drawings. Below the shelves g' and h' are formed air-inlets p and q, and also at k, the air taking the direction as indicated by the arrows. When the grain leaves the tube or

50 spout e, it will fall into the tube f and down onto the inclined shelf g', which will in turn conduct it to the tube g, where it will fall onto the shelf h', from which it falls into the tube h, onto the shelf i', and then through the spout r' out of the machine. It will now be

55 seen that the grain before leaving the machine is perfectly scoured, polished, and cleaned. When first fed into the machine, the grain, by its downward travel, is thoroughly scoured by the casings A B, being also cleared

60 of any dust by a strong current of air drawn by the fan through the casing A, the grain, casing B, and down into and out of the fan-

70 chamber, as indicated by the arrows. The grain is then distributed to the brush, which thoroughly cleans and polishes it, and, if still mixed with any dirt or foreign substances, is cleared thereof by a current of air drawn by the fan from the chamber V and opening G⁴ up through the brush, out of the casing, and down into and out of the fan-chamber, as also indicated by arrows. The grain is then carried to the separator, from which it issues, as before described. If upon entering the separator the grain is mixed with broken or injured grain, or smaller and inferior grain, or if mixed with dust or foreign substances, this inferior quality of grain is caught up by the air-currents as the grain falls from the shelves g' h', and carried up the tubes f, g, and h into the chamber S, the speed of said inferior grain decreasing as it rises. However, if the good or perfect grain is carried up by a momentary increase of speed, or any other cause, such grain will accumulate and remain in suspension until enough has accumulated to decrease 90 the action of the air-current or charge it with such weight that it will allow the good grain to drop back again into the volume of like grain passing out of the machine. The lighter or inferior grain, after passing into the chamber S, is carried over the side t of the chamber into the adjacent chamber O, and down into the vacuum-chamber P, in which all damaged particles of grain, &c., lodge and pass out at valve r, which is held closed by the suction 100 of air passing up the chamber or tube Q, partially separated from the chamber O by the partition O', until the weight of said lodged grain is sufficient to force the valve back and allow it to escape. The current of air passes 105 up through the chamber Q, over the top of the side R, and down the chamber N, attached to said chamber Q, and through the fan-easing to the fan. A valve, u, is placed in the chamber Q, adapted to be operated from outside, and thereby regulate the suction or current of air in said chamber Q to the quality of grain being cleaned.

110 As many slight changes might be resorted to without departing from the spirit and scope of my invention, I would have it understood that I do not limit myself to the exact construction shown and described, but consider myself at liberty to make such changes as fairly fall within the spirit and scope of my invention.

115 Having fully described my invention, what I claim as new, and desire to secure by Letters Patent, is—

120 1. The combination, with a revolving shaft, a perforated casing secured to said shaft, and a brush secured to the shaft below the casing, of perforated stationary casings surrounding said movable casing and brush, and a fan secured to said shaft below the brush.

125 2. The combination, with a shaft journaled in a suitable frame, a perforated casing secured to the shaft, and a cylindrical brush located below the perforated casing and revolv-

ing with the shaft, of a stationary perforated casing surrounding the movable casing, and a stationary perforated casing surrounding the brush.

5 3. The combination, with a revolving shaft, a perforated casing secured thereto, a stationary perforated casing surrounding the movable casing, a cylindrical brush rotated by the shaft, and a perforated casing inclosing the brush, of a plate located between the upper and lower stationary casings and provided with discharge-openings and feed-regulating devices, substantially as described, for regulating the feed of grain to the brush.

15 4. The combination, with a shaft journaled in a suitable frame, of a brush secured to the shaft, a casing, the top of said brush being formed concave, a scouring-chamber leading to said brush, and the plates F and T, situated 20 between the scouring-chamber and brush, substantially as and for the purpose described.

5 5. The combination, with a shaft and a scouring-chamber consisting, essentially, of a movable and stationary casing, of a brush 25 having air spaces or openings therein and located below the scouring-chamber, a perforated casing surrounding the brush, and an air-chamber communicating with the inside of the brush, substantially as set forth.

30 6. The combination, with a revolving shaft and a scouring-chamber consisting, essen-

tially, of a movable and stationary perforated casings, of a brush revolving with the shaft and having openings therein for the passage of air, a perforated casing surrounding the brush, an air-chamber located below the brush and communicating with the interior thereof, and a fan for exhausting the air from said chamber, substantially as set forth.

7. The combination, with a shaft journaled 40 in a frame, of the brush C, secured to the shaft, plates F H I, casings E G, cylinders A B, a fan, and a fan-chamber, all of the above parts combined and adapted to operate substantially as and for the purpose described. 45

8. The combination, with the shaft, the perforated movable casing and brush secured to said shaft, and the stationary perforated casings surrounding said movable casing and brush, of the separator in open relation with 50 the chamber in which the brush is located, and the fan, all of the above parts being constructed and arranged substantially as set forth.

In testimony whereof I have signed this 55 specification in the presence of two subscribing witnesses.
